UNITED STATES PATENT OFFICE.

GEORGE O. DRAPER, OF HOPE DALE, MASSACHUSETTS, ASSIGNOR TO THE DRAPER COMPANY, OF SAME PLACE AND PORTLAND, MAINE.

SPINDLE AND BEARING.

SPECIFICATION forming part of Letters Patent No. 609,759, dated August 23, 1898.

Application filed December 18, 1897. Serial No. 662,366. (No model.)

To all whom it may concern:

Be it known that I, GEORGE O. DRAPER, of Hopedale, county of Worcester, State of Massachusetts, have invented an Improvement in 5 Spindles and Bearings, of which the following description, in connection with the accompanying drawings, is a specification, like letters on the drawings representing like parts.

This invention relates to that class of spinning-spindles wherein the tapering pintle of the spindle enters a correspondingly-tapered bolster located in the bolster-case; and it has for its object the production of means for securing the proper fit of the pintle in the bolster 5 in a simple and efficient manner, the bolster being adjusted vertically until the proper fit is attained.

In my present invention the bolster is sustained within the bolster-case by a support on o and relative to which the bolster is vertically adjustable, the bolster having a frictional engagement with and being adapted to slide longitudinally in the support.

Figure 1 is a vertical section of a spindle-bearing with one embodiment of my invention applied thereto. Fig. 2 is a perspective view of the bolster-support. Figs. 3 and 4 are sectional and perspective views of a modified form of support; and Fig. 5 is yet another o modification of my invention, to be described.

The spindle A, having a tapering lower end or pintle and provided with a sleeve-whirl A², the bolster-case B, having a threaded shank B², and the nut B³, to clamp the case 5 to the rail C, may be and are of usual or well-known construction.

A step or end bearing D for the spindle is shown in Fig. 1 as resting on the bottom of the closed lower end of the bolster-case and o filling the same.

The bolster B^x may be of any suitable construction, and it is shown as sustained by a support F, shown as a sleeve split longitudinally at f, Fig. 2, and resting on the step D, the lower end of the bolster being telescopically connected with and held by friction in the support. In order to adjust the bolster, it is pushed more or less into the support and held frictionally thereby in adjusted vertical o position.

I have omitted any packing for the bolster, and the same may be of any suitable or well-known character.

In Figs. 3 and 4 I have shown the support

F^x as closed at its lower end and slotted longitudinally at f^x to attain the desired expansibility, the spindle-step D in this instance resting on the bottom of the support, the adjustment and support of the bolster being effected as before.

60

Still another modification is shown in Fig. 5, the cup-like support F' being made non-expansible and adapted to receive the lower end of the bolster B⁵, the latter being reduced in thickness at b and slotted, as at b⁵, to make 65 a tight frictional fit in the support. The reduced end of the bolster does not touch the pintle of the spindle to obviate any pinching of the latter in adjusting the bolster.

In any case the adjustment of the bolster 70 to secure the proper fit of the pintle therein is readily and quickly effected, and the construction is simple, cheap, and durable.

Having fully described my invention, what I claim, and desire to secure by Letters Patent, is—

1. A bolster-case, a bolster, a concentric support telescopically connected with and frictionally engaging the bolster and on which support said bolster is vertically adjustable, 80 and a spindle-step unconnected with the bolster.

2. The combination with a bolster, of a split, sleeve-like support in frictional engagement with the lower end of and to adjustably sustain the bolster at any desired height relative to said support.

3. A spindle having a tapered bearing portion, a bolster therefor, a split bolster-support engaging with a sliding fit the lower end 90 of the bolster, to adjustably support the bolster, and a spindle-step below the engaging portion of the bolster and its support.

4. A spindle having a tapered bearing portion, a step to support the spindle, a bolster 95 above the step, and an intermediate support for the bolster, said support frictionally engaging and substantially surrounding the lower end of the bolster, for the purpose set forth.

100

In testimony whereof I have signed my name to this specification in the presence of two subscribing witnesses.

GEORGE O. DRAPER.
